UNITED STATES PATENT OFFICE

ARTHUR E. BENSON, OF BOSTON, MASSACHUSETTS, ASSIGNOR TO DRAPER CORPORATION, OF HOPEDALE, MASSACHUSETTS, A CORPORATION OF MAINE

LOOM FILLING FORK AND PROTECTOR CONTROLLING MECHANISM

Application filed September 22, 1930. Serial No. 483,532.

This invention relates to manually controlled mechanism for rendering inactive both the usual protector mechanism and the usual filling fork mechanism of a loom when the loom is started so that the loom may be run by power without the filling being present.

When a loom, as is usual, is provided with a protector mechanism which acts to stop the loom when the shuttle is absent from the box and with a filling fork mechanism which also acts to stop the loom when the filling is absent in the shed, it is obviously impossible to start and run the loom with the filling or the shuttle absent because one or both of these mechanisms will act immediately again to stop the loom. But it is frequently desirable, after the loom has been stopped, especially as a result of breakage or absence of the filling, to start the loom and run it for a few picks either without the shuttle or without the filling, as, for example, to permit the finding of the pick. If the shuttle is not present or if the shuttle does not box properly, owing to the slow speed at which the loom is run, the usual protector mechanism will immediately act again to stop the loom. So also if the shuttle is not present or if there is no filling present in the shuttle, the usual filling fork mechanism will immediately act again to stop the loom.

The present invention provides simple and effective mechanism preferably associated with the usual controller or shipper handle which is moved from an "off" position, where it stands when the loom is stopped, to an "on" position to start the loom, which mechanism is manually operated to render either or both the protector mechanism and the filling mechanism inactive so that the loom may be run without the shuttle or without the filling as long as this manually controlled mechanism is operated.

The nature and objects of the invention will appear more fully from the accompanying description and drawings and will be particularly pointed out in the claims.

As the general construction and operation of a loom provided with protector mechanism acting to stop the loom when the shuttle

is absent or improperly boxed and with filling fork mechanism acting to stop the loom when the filling is absent in the shed are well known and familiar to those skilled in the art, and as the present invention is concerned only with means for rendering these mechanisms inactive to stop the loom and permit the loom to be run either without the shuttle or without the filling, it is only necessary here to illustrate those parts of a loom directly concerned with a preferred embodiment of the invention.

In the drawings:

Fig. 1 is a side elevation of a portion of the loom.

Fig. 2 is an enlarged detail chiefly in side elevation of a portion of the filling fork mechanism.

The loom illustrated comprises the usual frame, a portion of one of the side frames 70 1 being shown. These side frames are connected by the usual breast beam 2. There is also shown a portion of one of the lay swords 3 supporting the lay 4 which is provided at each end with a shuttle box having 75 the front wall 5 and the back wall 6.

The protector mechanism illustrated is of a generally familiar type. A protector shaft or rod 7 is journalled in the lay swords and extends transversely of the loom beneath the 80 lay. A protector finger 8 extends upward from this rod and is provided with a stud 9 abutting the movable rear wall 6 of the shuttle box. A dagger 10 extends forward from the protector rod 7. A frog 11 is mounted to slide back and forth on the loom frame, being normally held in its rearward position by a spring, not shown. This frog is provided with a projection 12 and the arrangement is such that when the frog 11 with its 85 projection 12 is moved forward, it will act to effect the stopping of the loom. Only a portion of the loom stopping mechanism is shown. This mechanism comprises a brake handle 13 fulcrumed on the stud 14 and provided with an arm 15 in the path of the projection 12 and a controller or shipper handle 16 also fulcrumed on the stud 14 and provided with an arm 17 having mounted thereon an adjustable screw 18 engaging the lateral 90

projection 19 on the arm 15. When the frog 11 is moved forward, it engages the arm 15 and thus rocks both the brake handle 13 and the controller or shipper 16 from the "on" or starting position shown in Fig. 1 to the left to the "off" or stopping position, and these parts are suitably connected to mechanism not necessary to illustrate for applying the brake and throwing off the power or otherwise stopping the loom.

When the shuttle is properly boxed in the shuttle box, the rear wall 6 is pressed to the left, viewing Fig. 1, rocking the protector finger 8 and the protector rod 7 into a position that holds the dagger 10 in a path above the frog or the steel 20 of the frog as the lay beats up. If, however, the shuttle is absent from the box or improperly boxed, the protector finger 8 is not pressed backward or to the left and stands in the position shown in Fig. 1 so that as the lay beats up, the dagger 10 moves in a path which brings it into engagement with the steel 20 of the frog and the frog is moved forward and the loom is stopped.

The filling fork mechanism illustrated is also of a familiar type. A filling fork slide 21 is mounted to slide back and forth on the breast beam. A filling fork comprising the depending tines 22 and the looped end 23 is pivoted at 24 on the rearward end of the filling fork slide. A weft hammer 25 fulcrumed at 26 is constantly vibrated by the mechanism of the loom. At its upper end the weft hammer has pivoted thereto at 27 a hook or catch 28 guided on the cross bar 29 of the slide. If the filling is present in the shed when the lay beats up, it engages the tines of the fork and rocks the fork so that its looped end 23 will not be caught by the hook or catch 28 on the weft hammer. If, however, the filling is absent in the shed, the fork will not be tilted and the catch 28 will engage the looped end 23 of the filling fork, and as the weft hammer swings forward, the filling fork slide will be carried bodily forward and through usual mechanism, not necessary further to describe, effect the stopping of the loom.

The present invention has for its object, as already pointed out, to provide manually controlled means for rendering both this protector mechanism and this filling fork mechanism inactive so that when this manually controlled means is operated, the loom may be run without the shuttle or without the filling. This enables the weaver to run the loom under its own power for a few picks without the shuttle or without the filling being present, which is very desirable, particularly in finding the pick.

In the preferred form of the invention illustrated, a three-armed lever is fulcrumed at 30 on the loom frame. The upstanding arm 31 is provided with a roller 32. The

forwardly extending arm 33 is provided with a forwardly extending rod 34. An arm 35 is secured to the protector rod 7 in the path of the roller 32 and is so arranged that when the three-armed lever is in the position illustrated in full lines, this arm 35 engaging the roller 32, as the lay beats up, will rock the protector rod and hold it in the position assumed if the shuttle is in the box, thus holding the dagger 10 in a path which passes above the frog steel 20.

A shield 36 is associated with the weft hammer, in the construction illustrated being fulcrumed thereon at 37. A rod 38 is pivoted to the forward end of this shield and extends downwardly therefrom and is looped at its lower end to fit over the rod 34. Normally the shield 36 is depressed by gravity so as to be below the catch 28. But if the rod 38 be depressed, the shield 36 is moved into the position shown in full lines in Figs. 1 and 2, guarding the catch 28 so that it cannot engage the looped end 23 of the filling fork.

Consequently it will be seen that if the three-armed lever is swung into the position shown in full lines in Fig. 1, both the protector mechanism and the filling fork mechanism will be rendered inactive because, in the case of the former mechanism, the dagger 10 will be guided in a path above the frog steel 20 as the lay beats up and because, in the case of the latter mechanism, the rod 34 will pull down the rod 38 and hold the shield 36 guarding the catch 28 so that the weft hammer cannot engage the filling fork and move the filling fork slide forward.

This three-armed lever is manually operated to move it into the position to render the protector mechanism and the filling fork mechanism inactive by a manually operated means and preferably a manually operated means associated with or adjunctive to the controller or shipper handle 16. In the preferred form of this invention, this manually controlled means is so arranged that when the hand of the operative grasps the shipper handle 16, the thumb of the same hand may be employed to operate this means and hold the protector mechanism and the filling fork mechanism inactive when the shipper handle 16 is moved to and held in the "on" or starting position, thus allowing the loom to be run by power without the shuttle or the filling being present.

In the construction illustrated, a plunger 39 is mounted in a casing 40 on the shipper handle and this plunger is normally held elevated by the spring 41 in the casing. A Bowden wire has its sheath 42 secured in the casing with its core 43 abutting the plunger. At the other end the sheath of the Bowden wire is secured at 44 to the loom frame adjacent the third or depending arm 45 of the three-armed lever and the core 43 is secured directly to this arm 45.

The operation of the mechanism will now be apparent. When the loom has been stopped through the operation of the protector mechanism, the filling fork mechanism or 5 otherwise, the controller or shipper handle will stand in the "off" or stopping position shown in Fig. 1. If now the operative desires to start and run the loom without the shuttle or without the filling, he seizes the 10 shipper handle in his hand, places his thumb on the plunger 39 and depresses it into the position shown in Fig. 1. This forces the core 43 through the sheath and swings the three-armed lever from its normal position, 15 shown in dotted lines in Fig. 1, to the position shown in full lines, thus rendering both the protector mechanism and the filling fork mechanism inactive or ineffective to stop the loom. Just as long as the plunger is held 20 depressed, these mechanisms will be held inactive.

Having thus described the invention, what is claimed as new, and desired to be secured by Letters Patent, is:

25 1. A loom comprising a lay provided with shuttle boxes, protector mechanism rendered active upon the absence of the shuttle from the shuttle box, filling fork mechanism rendered active upon the absence of the filling in 30 the shed, means acting to stop the loom whenever either the protector mechanism or the filling fork mechanism is rendered active, and manually operated means for holding both said protector and said filling fork mechanisms inactive, whereby the loom may be 35 run without filling or without the shuttle.

2. A loom comprising a lay provided with shuttle boxes, loom stopping means acting to stop the loom upon absence of filling in the 40 shed or upon absence of the shuttle from the shuttle box, and manually operated means for holding said loom stopping means inactive whereby the loom may be run without filling or without the shuttle.

45 3. A loom comprising a lay provided with shuttle boxes, a frog acting when moved forward to stop the loom, a dagger carried by the lay and held by the shuttle when boxed to move in a path above the frog but engaging 50 and moving the frog forward when the shuttle is absent from the box on the beat-up, a shipper handle manually movable from starting to stopping position, a spring-pressed plunger on the shipper handle operable by the thumb of the hand operating the shipper handle, and means operated by the plunger and acting when the plunger is depressed to deflect the dagger into a path such that it will not engage the frog upon the beat-up 55 whereby the loom may be run without the shuttle by holding the plunger depressed.

60 4. A loom comprising a lay provided with shuttle boxes, a frog acting when moved forward to stop the loom, a dagger carried by the 65 lay and held by the shuttle when boxed to

move in a path above the frog but engaging and moving the frog forward when the shuttle is absent from the box on the beat-up, filling fork mechanism rendered active upon the absence of the filling in the shed to effect 70 the stopping of the loom, a shipper handle manually movable from starting to stopping position, a spring-pressed plunger on the shipper handle operable by the thumb of the hand operating the shipper handle, and means operated by the plunger and acting when the plunger is depressed to deflect the dagger into a path such that it will not engage 75 the frog upon the beat-up whereby the loom may be run without the filling and without 80 the shuttle.

5. A loom comprising a lay provided with shuttle boxes, a controller manually movable between "off" and "on" positions to stop and start the loom, protector mechanism rendered active upon the absence of the shuttle from the shuttle box to move the controller to "off" 85 position and stop the loom, and means adjunctive to the controller and operable by the hand while grasping the controller to hold the protector mechanism inactive when the controller is manually moved to "on" position and thus allow the loom to be run without the shuttle.

6. A loom comprising a controller, filling fork mechanism rendered active upon the absence of the filling in the shed to move the controller to "off" position and stop the loom, and means adjunctive to the controller and operable by the hand grasping the controller in its "on" position to hold the filling fork mechanism inactive and thus allow the loom to be run without the filling when the controller is in "on" position.

7. A loom comprising a lay provided with shuttle boxes, a controller manually movable between "off" and "on" positions to stop and start the loom, protector mechanism rendered active upon the absence of the shuttle from the shuttle box to move the controller to "off" position and stop the loom, filling fork mechanism rendered active upon the absence of the filling in the shed to move the controller to "off" position and stop the loom, and means adjunctive to the controller and operable by the hand operating the controller to hold both the protector mechanism and the filling fork mechanism inactive when the controller is moved to "on" position, whereby the loom may be run without filling and without the shuttle.

8. A loom comprising a filling fork slide, a filling fork pivoted thereon, a weft hammer acting to engage the filling fork when the weft is absent in the shed and move the filling fork slide forward and effect the stopping of the loom, a shield associated with the weft hammer and movable into position to prevent the engagement of the filling fork by the weft hammer, a shipper handle manually movable 125

from starting to stopping position, a spring-
pressed plunger on the shipper handle oper-
able by the thumb of the hand operating the
shipper handle, and means operated by the
plunger and acting when the plunger is de-
pressed to move the shield into position to
prevent the engagement of the filling fork by
the weft hammer whereby the loom may be
run without filling by holding the plunger
depressed.

In testimony whereof, I have signed my
name to this specification.

ARTHUR E. BENSON.
